UNITED STATES PATENT OFFICE

JAMES B. STEWART, OF BROOKLINE, MASSACHUSETTS, ASSIGNOR TO THE JOHN BRIGHT SHOE STORES CO., OF BOSTON, MASSACHUSETTS, A CORPORATION OF MASSACHUSETTS

DESIGN FOR A STORE FRONT

Application filed February 26, 1929. Serial No. 30,214. Term of patent 14 years.

To all whom it may concern:

Be it known that I, JAMES B. STEWART, a citizen of the United States, residing at Brookline, in the county of Norfolk and State of Massachusetts, have invented, a new, original, and ornamental Design for a Store Front, of which the following is a specification, reference being had to the accompanying drawing, forming part thereof.

Fig. 1 is a perspective view of a store front embodying the new design;

Fig. 2 is a section on the line 2—2, Fig. 1.

I claim:

The ornamental design for a store front, as shown.

In testimony whereof, I have signed my name to this specification.

JAMES B. STEWART.
